H. ZINS

VETERINARY OBSTETRICAL FORCEPS

Filed Nov. 3, 1927

Inventor
H. Zins.

By *Alfredo J. Zins* Attorney

UNITED STATES PATENT OFFICE.

HUBERT ZINS, OF WABASSO, MINNESOTA.

VETERINARY OBSTETRICAL FORCEPS.

Application filed November 3, 1927. Serial No. 230,814.

This invention relates to an obstetrical forceps adapted to be used for the purpose of delivering a pig which due to its size is held against natural delivery by the pelvic bone of the sow, and has for one of its objects to provide a novel, simple and highly efficient instrument of this character which shall be so constructed as to permit it to be readily inserted into the vagina and engaged with the jaw of the pig.

With the foregoing and other objects in view, the nature of which will appear as the description proceeds, the invention consists in the construction, combination and arrangement of parts hereinafter fully described and claimed, and illustrated in the accompanying drawing, wherein:

Figure 1 is a view in side elevation of the forceps,

Figure 2 is a top plan view of the forceps, and

Figure 3 is a sectional view taken on the plane indicated by the line 3—3 of Figure 1.

The forceps comprise elongated straight jaws 1 and 2 which have their rear end portions reversely bent and connected by a pivot 3. Elongated handles 4 and 5 extend rearwardly from the jaws 1 and 2, respectively, and they are provided with hooked rear terminals 6 and 7, respectively, which are adapted to prevent the handles from slipping from the hands. The jaw 1 is provided at its front end with an upwardly extending curved beak 8. The jaw 1 and its beak 8 are circular in cross section, the free end of the beak is rounded, and the jaw gradually tapers in the direction of the beak. The jaw 2 is provided at its front end with a flat beak 9 which extends directly forward therefrom to a point forwardly beyond the beak 8. The beak 9 is elliptical in contour, and the edge thereof is rounded. The jaw 2 is circular in cross section and tapers gradually in the direction of the beak 9.

In practice, when the mouth of the pig, which due to its size cannot pass the pelvic bone of the sow, can be felt with one finger, the forceps are inserted into the vagina with the jaws 1 and 2 in closed relation and with the flat beak 9 in contact with the finger, which is used to guide the beak 9 into the mouth of the pig until the curved beak

8 reaches the lower jaw. The forceps are then manipulated to slightly open the jaws 1 and 2, and they are then pushed further into the vagina until the curved beak 8 reaches the bifurcation of the lower jaw. The forceps are then closed to grip the lower jaw and thereafter traction is applied to effect the delivery of the pig.

As the jaws 1 and 2 are of considerable length, and as the flat beak 9 extends forwardly beyond the curved beak 8, the jaw of the pig may be engaged with comparatively little effort and in a comparatively short time. Furthermore, the length of the jaws 1 and 2 permit them to be brought into comparatively close relation when they are deep in the vagina, and the extension of the flat beak 9 beyond the curved beak 8 permits the flat beak to act as a guide in placing the flat beak into the mouth of the pig. As the jaws 1 and 2 and the curved beak 8 are round in cross section, as the free end of the curved beak is rounded, and as the edges of the flat beak 9 are rounded, it is impossible to injure the sow or pig during the insertion of the forceps into the vagina and during their engagement with the mouth. When necessary to use other instruments before the final delivery of the pig, the forceps may be held in place, with the jaws 1 and 2 engaging the mouth of the pig, by means of a string or rubber band 10 applied to the terminals 6 and 7, as shown in Figure 1. The forceps are also adapted, as will be apparent, to be used for the purpose of delivering the fetus of dogs, cats and other small animals.

It should be understood that the drawing is merely illustrative and does not pretend to give exact proportions. Furthermore, the said drawing is illustrative of a preferred construction, it being my expectation that various changes and modification may be made without departing from the spirit and scope of my invention.

What is claimed is—

1. A forceps comprising a pair of elongated straight jaws, means pivotally connecting the jaws, handles carried by the jaws, a curved beak carried by the forward end of one of the jaws and extending therefrom in the direction of the other jaw, and a flat beak extending directly forward from the

forward end of the other jaw to a point beyond the curved beak.

2. A forceps comprising a pair of elongated jaws, one of the jaws being longer than 5 and extending forwardly beyond the other, means pivotally connecting the jaws, handles carried by the jaws, a curved beak carried by the short jaw, and a flat beak of elliptical

contour carried by the long jaw and extending forwardly therefrom to a point beyond 10 the curved beak, the jaws and curved beak being circular in cross section, and the free end of the curved beak and the edge of the flat beak being rounded.

In testimony whereof I affix my signature.
HUBERT ZINS.
